(74) Attorney, Agent, or Firm — True Shepherd, LLC;
Andrew Cheng(57) **CLAIM**

The ornamental design for a mattress, as shown and described.

DESCRIPTION

FIG. 1 is a front, right and top perspective view of a mattress, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 1 comprising a corner.

The dash dot dash broken lines shown in FIG. 1 and FIG. 9 are for the purpose of depicting areas of enlargement and form no part of the claimed design.

1 Claim, 9 Drawing Sheets(56)
